SUPERHEATER ELEMENT WITH TRIFURCATE GROUPS

André Philippe Jean Huet, Paris, France, assignor to Combustion Engineering-Superheater, Inc., a corporation of Delaware

Application June 3, 1947, Serial No. 752,225
In France July 11, 1941

Section 1, Public Law 690, August 8, 1946
Patent expires July 11, 1961

13 Claims. (Cl. 257—248)

1

This invention relates to steam superheater elements for use in locomotive and other smoke tube boilers. It is concerned particularly with elements of the kind in which the steam, in traversing that portion of the element which lies in a smoke tube, flows only once in each direction and has a plurality of relatively small pipes or tubes conveying steam in one direction with a single return bend at the fire box end of the element effecting the required reversal in the direction of steam for return flow through a second group of small pipes conveying the steam in the opposite direction.

It is an object of the present invention to provide a steam superheater element of the kind referred to above in which the junction or union of the fire-box ends of the tubes comprised in the group of small tubes conveying steam in one direction and their connection to the tube or tubes conveying steam in the opposite direction shall be of such construction and so disposed in the smoke tube as to afford relatively little obstruction to the flow of gases through the smoke tube.

The most vulnerable portion of a steam superheater element is that at its fire box end, due of course to the proximity of such portion to the furnace, and it is another object of the invention to provide a multiple pipe element of the kind indicated above in which the construction shall be such that a relatively high steam speed may obtain in the fire box end portion of the element resulting in an effective cooling thereof. A further object is to provide an element of improved construction in which the fire box end portion shall be such that its manufacture from heat resisting steel tubing will be facilitated.

Some locomotive boilers have the fire box end portions of the smoke tubes accommodating the superheater elements reduced in diameter and it is still another object of the present invention to provide a multiple pipe element of the kind with which the invention is concerned in which the fire box end portion thereof may extend into the contracted part or throat of the smoke tube without so reducing the cross-sectional area of that part of the smoke tube available for the gases that flow of the latter will be unduly restricted or throttled, thus enabling the return end portion of the element to be located in such a smoke tube nearer to the fire box than is the case with multiple pipe elements of the kind above indicated as have been constructed heretofore.

In a steam superheater element according to

5 this invention the fire box ends of the several tubes conveying steam in one direction are united at a point spaced from the return bend of the element and are connected with the tubes conveying steam in the opposite direction by a single conduit. Such conduit may include the said return bend and the element thus have a fire box end portion comprising only two tubes.

10 According to the invention the joining of the two bundles of admission and return tubes is carried out with the aid of a single tube length joined by forging or welding on the one hand to the bundle of admission tubes, on the other hand to the return flow tubes. The said single tube 15 can be straight and disposed on the axis of the steam tube or it can be bent and in this case the two points of junction of the tube with the two bundles can be placed non-symmetrically in the smoke tube in such fashion as to insure at the 20 interior of the latter a judicious distribution of the different branches of the bundles whose tubes are preferably formed with offsetting bends and disposed so as not to oppose the passage of gas and on the other hand in such fashion as to 25 permit direct access of the gas to the central part of the smoke tube.

30 It is envisioned that the single tube can be of a smaller section than the sum of the tubes of the bundle so as to decrease the obstruction of the 35 passage of gas in the smoke tube and at the same time to increase the speed of flow of steam in the said bend so as to obtain a greater carrying in this location situated at the entrance to the smoke tube and particularly exposed to the hottest gas. The variation in the section of the junction tube can advantageously progressively increase and decrease in size.

40 The invention will be best understood upon consideration of the following detailed description of illustrative embodiments thereof when read in conjunction with the accompanying drawings in which:

45 Figure 1 is a fragmentary sectional view of a boiler flue showing mounted therein the fire-box end of a superheater unit embodying the present invention;

Figure 2 is a similar view as seen at right angles to Figure 1;

50 Figures 3 and 4 are transverse sectional views along the correspondingly designated lines in Figure 1;

Figures 5 to 8 are views corresponding respectively to Figures 1 to 4 but showing another constructional embodiment of the superheater unit in accordance with the invention.

Referring to Figures 1 and 2 it will be seen that the superheater element located in the smoke tube *a* is made up of a bundle of three tubes *b*, *c*, and *d* which are traversed by the steam admitted to the element and flowing in the direction of the arrows. The tube *a* is mounted in the usual manner in a tube sheet at the fire box end of the boiler. The bundle of return flow tubes likewise consists of three tubes *f*, *g*, *h*, which are traversed by the superheated steam flowing in the direction of the arrows. The relative disposition of the admission tubes *b*, *c* and *d* and the return flow tubes *f*, *g*, and *h* within the interior of the smoke tube *a* is shown in Figure 3. It may be seen that the return flow tubes *f*, *g*, and *h*, are located centrally of or at the interior of the bundle of admission tubes *b*, *c*, *d*, so as to be protected by the latter which in effect form a heat shield.

According to the invention the connection of the two tube bundles at the smoke box end is carried out through the aid of a single tube *i*. This tube is disposed in the case shown in Figures 1 and 2 along the axis of the flue. It is joined by means of a breeches piece *j* with the three return flow tubes *f*, *g*, and *h* and by a breeches piece *k* with the admission tubes *b*, *c*, *d*. This tubular connection *i* may be created as an extension of the rounded breeches piece *j* produced by forge welding the tubes *f*, *g*, *h*, together with the tube *i* projecting centrally from the group of tubes *f*, *g* and *h*. In effect the breeches *k* is formed by simultaneously forge welding the four tubes *b*, *c*, *d* and *i* together, the tube *i* which is of larger diameter being located centrally within the tube bundle *b*, *c* and *d* which are distributed uniformly around the tube *i* (Fig. 4).

The method of joining tubes by forge welding steps is now well known and need not be described in detail herein, it being sufficient to state that in such a process the end portions of two or more tubes to be joined, after being brought to welding heat, are placed in a female die and a male die or punch is introduced into the tube ends which splits and turns outwardly the appropriate portions of the opposed walls of adjacent tubes and after bringing such portions into abutting relation welds them together to form a common or union portion, sometimes known as a breeches-piece. The open end of this breeches-piece may be rounded and joined to another tube, or it may be arched over and closed by a swaging operation to form a return bend of a superheater or like element.

The tubes *b*, *c* and *d* are preferably formed with ogee bends near their extremities as may be seen at *e* in Figures 1 and 2 so as to permit their ends to be brought closer together to facilitate the forging of the breeches piece *k*. This bending extends far enough along the tubes so as not to produce an abrupt obstruction of the smoke tubes and to leave sufficient gas flow within the tube.

In the preferred embodiment shown in Figures 5 and 6 a separate tube *n* interconnecting the two tube bundles is bent 180° intermediate its ends at *l* and the two breeches pieces *k* and *j* are then welded thereto at *s*. As shown the breeches pieces *j* and *k* are disposed non-symmetrically within the flue *a*, the breeches-piece *j* being located on the axis of the flue while the breeches-piece *k* is offset towards the upper part of the tube (Fig. 5).

In this case also the bends *e* in the tubes *b*, *c* and *d* of the admission bundle extend far enough along their length so that in the region where

these tubes are drawn together there will not be an obstruction offered to the flow of the gas. The tubes of the two bundles being located within the flue as seen in Figure 7 are held in position by suitable spacers and supports not illustrated.

The cross-section of the tube *i* or *n* located in the zone of highest temperature in the flue *a* may be smaller than the sum of the sections of the tubes *b*, *c* and *d* of the admission bundle or of the aggregate cross section of the return flow tubes, in such manner as to increase the speed of flow of steam within the junction tube *n* which will then be more effectively cooled.

What I claim is:

1. A multi-tube superheater element comprising; a plurality of superheated steam or return flow tubes disposed in closely spaced and symmetrical relation about a longitudinal axis centrally located among them; a breeches piece joining said tubes together at one end thereof; a plurality of saturated steam or admission tubes disposed around said return flow tubes; a breeches piece integrally joining said admission tubes at one end thereof; individual open ended tubular portions forming parts of said breeches piece; and a junction tube interconnecting the open ends of said tubular portions of said two breeches pieces for connecting the group of admission tubes in series with the group of return flow tubes.

2. A superheater element as recited in claim 1 wherein said junction tube is an integral part of one of said breeches pieces.

3. A superheater element as recited in claim 1 wherein said junction tube is initially a separate tube having its two ends connected to the respective breeches piece.

4. A superheater element as recited in claim 1 wherein said breeches piece is initially a separate U-shaped tube having its ends connected to said breeches pieces.

5. A multi-tube superheater element comprising; a plurality of superheated steam admission tubes joined together at one end by an integrally formed open ended breeches piece; a plurality of superheated steam return flow tubes also integrally joined together at one end by a second open ended forge welded breeches piece spaced longitudinally from the breeches piece joining said admission tubes; and a junction tube having a U-bend formed therein intermediate its ends with the latter connected to said open ends of two breeches pieces.

6. A superheater element as recited in claim 5 wherein the return flow tubes are grouped centrally of the element with the admission tubes disposed around and outwardly of the latter.

7. A superheater element as recited in claim 6 wherein the return flow tubes are disposed in symmetrical arrangement close to and around a longitudinal axis located centrally among them.

8. A superheater element as recited in claim 6 wherein the breeches piece joining the return flow tubes is disposed on a longitudinal axis located centrally with respect to said return flow tubes and the breeches piece joining the admission tubes is disposed eccentrically with respect to said axis.

9. A superheater element as recited in claim 8 wherein said junction tube is located along a longitudinal axis located centrally with respect to said return flow tubes.

10. The method of manufacturing a metallic multi-tube superheater unit comprising; dispos-

ing a plurality of return flow tubes symmetrically about an axis parallel to their length and forge welding them together at one end to form a breeches piece; disposing a plurality of admission tubes around said group of return flow tubes and forge welding them together to form a second breeches piece; and joining the two breeches pieces together to connect the group of admission tubes in series with the group of return flow tubes.

11. The method of manufacturing a metallic multi-tube superheater unit comprising; disposing a plurality of return flow tubes symmetrically about an axis parallel to their length and forge welding them together at one end to form an open ended breeches piece; disposing a plurality of admission tubes symmetrically around said group of return flow tubes and forge welding them together to form a second open ended breeches piece; and joining the open ends of the two breeches pieces together by an intermediate relatively short tube to connect the group of admission tubes in series with the group of return flow tubes.

12. The method of manufacturing a metallic multi-tube superheater unit comprising; disposing a group of return flow tubes symmetrically about an axis parallel to their length and forge welding them together at one end to form an open ended breeches piece; disposing a group of admission tubes symmetrically around said group of return flow tubes and forge welding them together to provide a second open ended breeches piece forming the open end of said second breeches piece eccentrically with respect to the group of tubes and disposing it eccentrically with respect to the open end of the breeches piece for the group of return flow tubes; forming a return-bend loop in a relatively short tube; and joining

the open ends of said two breeches pieces to the ends of said relatively short tube with the two breeches pieces offset transversely of the unit for connecting the group of admission tubes in series with the group of return flow tubes.

13. The method of manufacturing a metallic multi-tube superheater unit comprising; disposing a group of return flow tubes symmetrically about an axis parallel to their length and forge welding them together at one end to form an open ended breeches piece; disposing a group of admission tubes symmetrically around said group of return flow tubes and forge welding them together to provide a second open ended breeches piece having its open end formed eccentrically with respect to the group of tubes and also disposed eccentrically with respect to the open end of the breeches piece for the group of return flow tubes; forming a return-bend loop in a relatively short tube; and joining the open ends of said two breeches pieces to the ends of said relatively short tube with the two breeches pieces offset transversely of the unit for connecting the group of admission tubes in series with the group of return flow tubes.
